UNITED STATES PATENT OFFICE.

WILLIAM M. BLECKER, OF CANTON, OHIO, ASSIGNOR TO EDWARD A. LANGENBACH, OF CANTON, OHIO.

DOUBLER.

Original application filed December 7, 1925, Serial No. 73,597. Divided and this application filed August 20, 1926. Serial No. 130,539.

This invention relates to apparatus for use in the continuous rolling of sheet bars, light plates or slabs into sheets of desired gauge, and the object of the improvement is to provide a doubling apparatus for use for example in carrying out a continuous sheet rolling method in which sheet bars, light plates or slabs are heated and passed continuously through a series of roughing mills, being matched or piled once, twice or more depending upon the gauge of sheets to be rolled, the pieces being then reheated and automatically doubled, if sheets under 22 gauge are desired, and then continuously passed through finishing rolls through side and end shearing apparatus, then through a continuous annealing furnace and finally through sheet levelling and opening mechanism and onto a cooling table; each succeeding stand of rolls throughout the train being operated at a higher speed than the preceding rolls in order to accommodate the increasing length of the bars or sheets as they are passed through each stand.

An embodiment of the invention is illustrated in the accompanying drawings, in which:

Figure 1 is a plan sectional view of the doubling apparatus, continuous open sheet furnace, the first stand of finishing mills and the first stand of edge straightening rolls for rolling sheets lighter than 22 gauge;

Fig. 2, a vertical longitudinal section of the same;

Fig. 3, a plan sectional view of the remaining alternate finishing mills and edge straightening rolls which succeed those shown in Fig. 2;

Fig. 4, a vertical longitudinal view of the same;

Fig. 5, an enlarged detached plan view of an improved doubling apparatus similar to the apparatus illustrated in Figs. 1 and 2; and

Fig. 6, a side elevation thereof.

Similar numerals refer to similar parts throughout the drawing.

This application is a division of my co-pending application for improvements in continuous sheet rolling apparatus and method, Serial Number 73,597, filed December 7, 1925.

In rolling sheets lighter than 22 gauge, a pile of sheets may be, during the process,

passed through a reheating furnace and after emerging from the furnace placed upon the improved automatic doubler of the present invention, a pusher 48 or the like being used for the purpose of placing the pile upon the doubler.

The improved doubler includes a table 50, one section of which as indicated at 51 is hinged at the center as at 52, a magnet 53 being carried by each section of the table close to the hinge joint.

As the pile is placed upon the table it engages a stop switch 53^a which automatically energizes through suitable electrical connections the magnets 53 holding the pile rigid on the table at points close to the hinge joint. At the same time a clutch C, connecting a suitable motor M with the rocker shaft 54, is electromagnetically thrown in, rotating this rocker shaft in the direction of the arrow shown in Figs. 2 and 6. This rocker shaft carried a rocker arm 55 connected, by a link 56, with the hinged section 51 of the doubler table throwing this hinged section into the position shown in dotted lines in Figs. 2 and 6, and since the pile is held by the magnets, only at points close to the hinge, the free ends of the sheets in the pile are permitted to open as the pile is doubled, forming a pack as illustrated at 57 in Figs. 2 and 6.

When the hinged section of the doubler table reaches the position shown in dotted lines in Fig. 2 it engages a stop 53^b which mechanically changes the clutch connection returning the hinged section to the normal position and at the same time the magnets are automatically deenergized by the switch spreaders 53^c and the pusher 48 operated to move the pack from the doubler and upon a roller table 58 by which it is conveyed through a continuous open sheet furnace 59 and thence to the first stand 60 of a second series of finishing rolls. The upper roll 61 of this stand is preferably of larger diameter than the lower roll in order to flatten the forward end of the heated pack as it is well known that there is a tendency for this forward end of the pack to bend or curve upward as it emerges from the furnace. The pack is then conveyed through a series of alternate edge straightening rolls 62 and finishing rolls 63, each edge straightening roll being considerably smaller in diameter

than the finishing rolls and being smaller at its center than at its ends so that the edges of the pack will be rolled down without striking the center of the pack and taking out the form of the preceding rolls, thus placing the pack in the next stand of finishing rolls as near to its original condition as possible and without breaking the pack open.

10 I claim:

1. A doubler including a table composed of two hingedly connected sections for receiving a pile of sheets, means for holding the pile adjacent to the hinge joint, and means actuated by the sheet pile for swinging the sections together to fold the pile into a pack.
2. A doubler including a table composed of two hingedly connected sections for receiving a pile of sheets, magnets adjacent to the hinge joint for holding the pile, and means actuated by the sheet pile for swinging the sections together to fold the pile into a pack.
3. A doubler including a table composed of two hingedly connected sections for receiving a pile of sheets, means for holding the pile adjacent the hinge joint, means actuated by the sheet pile for swinging the sections together to fold the pile into a pack, and means automatically controlling the operation of the holding means.
4. A doubler including a table composed of two hingedly connected sections for receiving a pile of sheets, means actuated by the sheet pile for holding the pile adjacent the hinge joint, means for swinging the sections together to fold the pile into a pack, and means automatically controlling the operation of the swinging means.
5. A doubler including a table composed of two hingedly connected sections for receiving a pile of sheets, means for holding the pile adjacent the hinge joint, means for swinging the sections together to fold the pile into a pack, and means actuated by the sheet pile for automatically controlling the operation of the holding and swinging means.
6. A doubler including a table composed of two hingedly connected sections for receiving a pile of sheets, means for holding the pile adjacent the hinge joint, means for swinging the sections together to fold the pile into a pack, and means actuated by the sheet pile for automatically controlling the operation of the swinging means.

sheet pile for automatically controlling the operation of the holding means.

7. A doubler including a table composed of two hingedly connected sections for receiving a pile of sheets, means for holding the pile adjacent the hinge joint, means for swinging the sections together to fold the pile into a pack, and means actuated by the sheet pile for automatically controlling the operation of the swinging means.

8. A doubler including a table composed of two hingedly connected sections for receiving a pile of sheets, electromagnetic means adjacent to the hinge joint for holding the pile, and means actuated by the sheet pile for swinging the sections together to fold the pile into a pack.

9. A doubler including a table composed of two hingedly connected sections for receiving a pile of sheets, electromagnetic means adjacent to the hinge joint for holding the pile, and means actuated by the sheet pile for automatically controlling the operation of the holding means.

10. A doubler including a table composed of two hingedly connected sections for receiving a pile of sheets, electromagnetic means for holding the pile adjacent the hinge joint, means for swinging the sections together to fold the pile into a pack, and means actuated by the sheet pile for automatically controlling the operation of the holding and swinging means.

11. A doubler including a table composed of two hingedly connected sections for receiving a pile of sheets, electromagnetic means for holding the pile adjacent the hinge joint, means for swinging the sections together to fold the pile into a pack, and means actuated by the sheet pile for automatically controlling the operation of the holding means.

12. A doubler including a table composed of two hingedly connected sections for receiving a pile of sheets, electromagnetic means for holding the pile adjacent the hinge joint, means for swinging the sections together to fold the pile into a pack, and means actuated by the sheet pile for automatically controlling the operation of the swinging means.

In testimony that I claim the above, I have hereunto subscribed my name.

WILLIAM M. BLECKER.
